UNITED STATES PATENT OFFICE

RUEL A. JONES, OF COVINGTON, KENTUCKY, ASSIGNOR TO R. A. JONES & COMPANY, INC., OF COVINGTON, KENTUCKY, A CORPORATION OF KENTUCKY

CARTON OPENING AND SQUARING APPARATUS FOR CARTON-FILLING MACHINES

Application filed September 6, 1928. Serial No. 304,190.

This invention relates to improvements in carton filling machines, and particularly to the apparatus for opening and squaring a collapsed or flat folded carton as successively ejected and advanced in their collapsed or flat form from a magazine or holder in which the cartons are deposited in horizontal position, adapting the lowermost cartons to be ejected one after another.

10 The invention primarily relates to carton opening and squaring mechanism movable horizontal and engaging a side wall or edge of a collapsed or partially collapsed carton sustained upon a table or track, and swinging the 15 walls of the carton to a normally open position and against square sided abutments or stops, one abutment or stop serving to arrest the advance of the carton as delivered from the magazine, the second engaging into the 20 carton, presenting a squared edge along a scored or folding line of two sides of the carton to hold or confine the carton against vertical displacement upon the track or table.

25 An object of the invention is to provide means for entering a flat knock-down rectangular carton and partially opening the same, whereupon it can be fully opened by pressure exerted in a horizontal direction 30 against one edge or side of the carton until contacting with a stationary squaring edge or surface.

Other objects and certain advantages will be more fully set forth in a description of the 35 accompanying drawings forming a part of this specification, in which:

Figure 1 is a fragmentary side elevation of a portion of the carton filling machine, and particularly of that portion embracing the present invention relating to the mechanism for squaring a flat or knock-down carton after being delivered from a magazine in which a stack or pack of flat cartons in horizontal position are deposited.

Figure 2 is a horizontal sectional view of the carton filling machine taken through the magazine and looking down on the stack of folded cartons in the magazine and a carton 100 acted on by the carton squaring mechanism.

Figure 3 is a sectional view taken on line 3—3, Fig. 2.

Figure 4 is a sectional view taken on line 4—4, Figure 1, illustrating the lever and cam for actuating the carton squaring mechanism.

Figure 5 is a diagrammatic view showing the carton partially opened by means of a transversely movable spear with the rear side and rear upper corner of the carton engaged by a horizontally reciprocating claw, the 60 claw in a forward motion moving the rear side of the carton and the square side of the spear.

Figure 6 is a sectional view taken vertically and longitudinally of the mechanisms for 65 ejecting or feeding the lowermost carton from the base of the magazine.

Figure 7 is a view taken on line 7—7, Figure 3, illustrating the means for holding the ejected carton against displacement laterally 70 of the guide rails as the spear is inserted therein.

Figure 8 is a diagrammatic view showing the relative positions of the spear and the carton as the carton is brought into alignment with the spear and prior to insertion of the spear.

Referring to the drawings, 10 indicates the machine frame of rectangular formation, built up of side rails 11 and end rails 12 supported upon legs 13. Standards 14 extend upwardly from the frame for supporting various overhead transmission devices not herein illustrated.

The present invention is directed primarily 85 to the mechanism for squaring a flat or knock-down carton of a carton filling machine of a character as disclosed in a prior patent issued to me, No. 1,472,364, dated October 30, 1923.

90 In such types of carton filling machines, a commercial form of collapsible or knock-down rectangular carton with closure flaps at its opposite ends is employed, the cartons being magazine in a flat or knock-down position. A bundle or stack of flat cartons is deposited within a vertically disposed magazine of the machine, positioning the cartons in a horizontal plane, allowing the lowermost cartons of the stack or pile to be successively 100

ejected or withdrawn by a reciprocating ejector blade and advanced to a carton squaring station, where the cartons are opened and squared and then delivered in such condition to a filling station for receiving the commodity, after which the filled carton is advanced, and during its advance the end closure flaps are tucked in and finally the filled and closed carton is discharged from the machine.

In the present instance, the carton, as it is being ejected from the magazine, is advanced in its horizontal position and tracked until the forward edge engages a stop or stationary abutment in the path thereof for definitely locating the carton with respect to a transversely movable spear engaged into the carton for partially squaring the same. The spear is provided with a squared edge against which the rear side of the carton is brought by a reciprocating claw engaging the rear upper edge of the partially opened carton and drawing or moving the upper and side walls to a squared position, one wall against the stationary abutment and the opposite wall against the square side of the spear.

In its squared position the carton is engaged by a transport mechanism, and after the spear has been withdrawn, advanced to a filling station, the filling mechanism and end flap closure mechanism not being disclosed herein.

As mentioned, the carton operated upon is the commercial type of rectangular tube form, having opposite face sides 5, 6, connected by opposite side walls 7—7. The ends of the carton are provided with end flaps 9 as extensions from the side walls and a tucking closure flap 8 extending from one of the face sides.

The flaps in the knock-down position of the carton are in plane with the carton walls from which they extend, and the tucking closure flaps protrude to overlap the end flaps, adapting the same to be individually manipulated for raising or inclining the same, to facilitate the entrance into the carton by a transversely reciprocable spear for a preliminary opening step, and to confine the carton upon the track or table during the opening or squaring operation.

The feeding and squaring mechanisms represent only a division of an organized machine, so that parts not directly or vitally concerned with the present improvements are omitted in the drawing disclosure and description of parts, and likewise, the power or transmission devices, including a number of cams and the like, for actuating the various elements of the feeding and squaring mechanisms in timed relation, are omitted, as such parts may be substantially the duplicate of those shown in the machine of said prior patent, or may represent any well known means for imparting the necessary movement to the various parts, the omission being made to

avoid unduly encumbering the present case.

The mechanism for successively ejecting the lowermost carton from the magazine and feeding the same forward to the squaring station, herein employed, follows the type of mechanism shown and described in a prior patent issued to me, No. 1,624,740, dated April 12, 1922. It comprises a magazine 15 for the stack of knock-down cartons vertically disposed upon the table or frame of the machine composed of a pair of forwardly disposed angle iron uprights 16 forming forward magazine corners and a pair of upright rearwardly disposed bars 17 forming the back of the magazine, this arrangement providing the rectangular magazine for containing and supporting the stack of folded cartons 18, the cartons lying horizontal one upon another, adapting the lowermost carton to be successively ejected.

The stack of cartons 18 is supported on a pair of cross rests 19, each comprising, a portion 20 attached to each channel iron upright and a rearwardly extending support finger 21. The lower ends of the rear magazine bar uprights are turned outwardly as at 22 and the rest fingers 21 are so related to the turned portion of the bars as to provide a narrow space 23 for the ejection of the lowermost flat carton.

The ejector or feeding mechanism comprises, a sucker element 24 for centrally engaging and drawing downwardly the lowermost carton, a separator element 25 horizontally inserted between the lowermost carton and the next adjacent carton, separated by centrally bowing of the lowermost carton on the rests 19, and an ejector element 26 comprising a pair of fingers 27 horizontally engaging the forward edge of the lowermost carton for sliding it laterally or forwardly from the base of the magazine through the space 23 over a table 28 to its squaring station.

The table 28 extends from a point below the magazine 15 and spaced away from the turned or foot ends 22 of the magazine bars. This table is suitably supported on the frame of the machine by means of a support 29 secured to the frame.

The ejected carton, indicated at 30, is advanced over the table by the ejector mechanism until its forward edge engages a vertically reciprocable stop element 31. The tucking flap 8 extending from one end of the carton during the travel of the carton is slightly elevated or inclined upwardly so as to slide over the upper inclined side of the reciprocable spear 33. The spear during the advance movement of the carton is stationary in its retreat position so as to receive the flap, with its head end in position to be shoved into the carton.

The flap sliding over the spear head has a tendency to slightly separate the face walls

of the flat carton, so that the edged end of the spear head is directed between the opposing face sides of the carton, the spear head being appropriately shaped to assure its entry into the carton.

5 The body portion of the spear is provided with a squared rear side, as shown in Figure 5, forming an abutment against which the rear side wall of the carton is drawn in squaring, the spear moving into the carton relative to the line of scoring as the juncture of the carton walls and substantially in line therewith, and approximately in sliding contact with the lower face wall of the carton to confine the carton upon the table and provide an edge over which the rear wall is bent. With the spear in such position within the carton, any forward pressure against the carton rear side wall will move the carton to its squared position about the spear.

10 The spear is mounted upon a slide 34 and projects beyond the end thereof so that it may be freely engaged into the carton for the desired length, with the head end 35 during the retreat position of the spear terminating at a point which will only engage with the closure flap 8 of the carton, thus, not interfering or obstructing the carton advance toward the stop 31. The head is appropriately formed by beveling its upper side and also its lower side, producing an angled knife edge adapting the head to be readily guided into the closed carton, its knife edge being in the plane slightly above the plane of the lower side wall of the carton, while the lower side of the body portion thereof is substantially in line with the upper surface of the lower face wall.

15 The slide 34 is mounted in the slideway 36 of a slide bracket 37 bolted to the frame providing for horizontal reciprocation of the spear at right angles to the table and longitudinal relative to the ejected carton, the slide being secured within the dovetail slideway by means of the usual gib plate 38.

20 A lever 39 having its upper end secured to the slide by means of a link 40 is pivoted or fulcrumed upon a bracket 41 attached to the side of the frame. The lower end of the lever 39 is pivotally connected to a rod 42 as an intermediate connection with the transmission means or mechanism, not shown, the lever providing the means for actuating the slide.

25 On the opposite side of the table from the spear a movable abutment 43 is provided for preventing lateral displacement of the carton induced by the insertion of the spear. This abutment is mounted on a swinging lever 44 fulcrumed on a standard 45 extending from and attached to the front frame and an actuating lever 46 is connected to the lower end of the abutment lever. The upper or engaging end of the abutment lever is 30 provided with the abutment in the form of

a plate, this plate presenting a side surface 48 toward the table and carton and a flat top surface 49 downwardly rounded toward its forward end. The purpose of the rounded forward end is to permit the carton side flaps 9 to slide over the abutment, the side flat edge being designed to engage the end edge of the base panel 5 of the carton which has no flap, this being apparent from Figure 7.

35 As a means for holding up the main tucking flap 8 of the carton on the side entered by the spear, a guide 52 is secured to the bracket 37 by means of a bracket or arm 53. The guide is formed of plate and presents an inclined top surface engaged by the flaps of the carton as ejected from the magazine and terminating in a horizontal portion 54 slightly above the level of the table. As shown in Figure 1, this horizontal portion 54 terminates slightly short of the position in which the carton is acted upon by the spear but is in engagement with the flaps until the upper flap 8 drops over the spear head.

40 After the spear has been inserted into the carton by reciprocation of the slide, the carton assumes the position shown in Figure 5 to be acted upon by a claw depending from a horizontally moving slide 55. The slide 55 is mounted on the upper face of an upper guide rail 56 toward the forward end thereof, the upper guide rail 56 being attached to the base flange of a standard 57. The upper guide or rail 56 is of the same width as the lower guide or table and terminates relative to the magazine so that the carton after ejection will be set up and squared between the respective rails for subsequent guided movement therebetween.

45 The slide 55 is of plate form, sliding upon the rail 56, said plate having flanges 59 overhanging the respective sides of the rail and fingers or lugs 60 depending from the respective side flanges for engaging the carton. The slide 55 is maintained for limited longitudinal movement on the table by means of screws 61 passing through longitudinal slots 62 in the upper portion and screwed into the upper rail.

50 The slide is reciprocated by means of cam and lever devices, as follows:

55 At the opposite end of the machine a vertical power shaft 63 carries a cam 64, the cam being engaged by a roller 65 secured to the outer or swinging end of a pivoted lever 66 mounted on a pivot bracket 67 by means of a pivot bolt 68, the bracket being secured to the side of the rear frame standard 69. A connecting rod 70 has one end secured intermediate of the lever and at its opposite end is secured intermediate of a second swinging lever 71, the last mentioned lever having its stationary end pivotally mounted on a bracket 72 secured to the front frame standard 14, and its swinging end having a double swinging connection to the slide by means of 130

a link 73, the link extending longitudinally of the slide and the connection being by means of pivot pins 74, 75.

5 A spring 76 is connected to the lever and to the front frame standard 14 for returning the slide after actuation by the cam and keeping the cam roller always in engagement with the cam. The slide in its action, as shown diagrammatically in Figure 5, moves the fingers or lugs 60 thereof into engagement with the forward longitudinal edge of the carton. The fingers or lugs are rounded as at 77 at their engaging side, so that the edge of the carton is engaged by cam surfaces.

10 15 Continued movement of the slide swings or rocks the carton on its base, in which position it is maintained by means of the spear and the carton is thereby squared against the spear forward edge. The reciprocating abutment also aids in the squaring of the carton in that it engages across the rear panel of the box, the abutment being at right angles to the table and the carton squared against these related parts.

20 25 Immediately after the squaring of the carton, swinging transport arms 78 having right angled forward formations are swung upward, the right-angled portion fitting about the base panel and forward panel of the carton, maintaining it for subsequent feeding in squared relation, the arms being pivotally connected as at 79 to a carriage element 80 by means of a cross shaft, and one thereof being of bell crank construction has a depending 30 35 arm 81 carrying one end of an operating rod 82.

30 35 The slide 55, the spear 33, and the abutment 31, are then rapidly withdrawn, the abutment 31 moving upwardly clear of the carton or the space between the rails. The carriage element is then slid rearwardly carrying the transport arms therewith, and consequently moving the squared carton longitudinally of the machine between the rails 40 45 into its next position.

40 45 The carriage element or block 80 is moved by means of a rod 83 pivotally connected to a depending lug 84 of the block, and the block is moved in a slot 85 in the table, being supported thereon by means of an attached plate 86 straddling and resting on the table adjacent the slot.

50 55 The swinging stop for preventing lateral displacement of the carton is swung clear immediately after the spear has been inserted. The timing of the various elements and the cams for imparting the movements thereto may be after any conventional manner and are not shown herein.

60 65 Having described my invention, I claim:

1. In a machine of the character disclosed for opening and squaring a flat collapsed carton, the carton having scored lines to determine the lines along which the carton will bend for opening, means for supporting the

carton, a spear-headed instrument having a square shouldered body movable for engagement into an end of the carton to partially open the carton, with the square shoulder entering the carton along one of the scored lines, and means movable horizontally of the carton for engaging the carton at an end beyond said spear-headed instrument, movable to open the carton against and in square with a shoulder of said spear-headed instrument.
